UNITED STATES PATENT OFFICE.

LAWRENCE E. CONNELLY, OF CLEVELAND, OHIO, ASSIGNOR OF ONE-HALF TO WILLIAM C. CONNELLY, OF CLEVELAND, OHIO.

STEAM-GENERATOR.

1,333,653.

Specification of Letters Patent. Patented Mar. 16, 1920.

Application filed March 31, 1919. Serial No. 286,371.

To all whom it may concern:

Be it known that I, LAWRENCE E. CONNELLY, a citizen of the United States, residing at Cleveland, in the county of Cuyahoga and State of Ohio, have invented certain new and useful Improvements in Steam-Generators; and I do hereby declare the following to be a full, clear, and exact description of the invention, such as will enable others skilled in the art to which it appertains, to make and use the same, reference being had to the accompanying drawings, and to the letters of reference marked thereon, forming part of this specification.

15 This application is a continuation in part, of the application filed by me February 20, 1918, Serial No. 218,261.

20 This invention relates to steam generator furnaces and improvements in the arrangement of baffle plates hereinafter explained and pointed out and illustrated in the accompanying drawing, in which:—

25 The figure is a sectional view of a steam boiler furnace with my invention installed therein.

30 In this drawing A indicates the mud-drum of a water-tube boiler of the Stirling type; A', A² and A³ indicate upper drums which are in circulatory connection with the mud-drum A by means of banks of tubes B, B' and B², and with each other by means of banks of tubes B³ and B⁴; all of usual construction. The drums and banks of tubes are inclosed in a boiler setting comprising 35 front and back walls C and C', side walls C², and cover C³. D indicates the usual fire-wall at the rear ends of the furnace grates D', extending from the bottom C⁴ of the furnace to the mud-drum A, in the usual manner.

40 Behind the bank of tubes B is a fire-baffle E extending from the mud-drum upwardly toward the drum A', and extending downwardly from the drum A² is a fire-baffle E', which does not reach to the mud-drum A. Between the fire-wall D and rear wall C', I erect a barrier or baffle F having in the upper end thereof a pocket F' containing pulverized asbestos or other suitable material; 45 suspended in the pocket F' and extending upwardly and transversely through the bank of tubes B² is a baffle plate G, which terminates at the rear side of the bank of tubes B'; said baffle plate being preferably curved as 50 shown, so that the space between it and the

mud-drum will be substantially uniform at all points.

The upper edge of the baffle plate G is suitably secured in a plurality of clamps H which are clamped around the rear series 60 of the bank of tubes B' so that the plate G will be suspended from said clamps so that its lower edge will not extend to the bottom of the pocket F. The plate G is provided with suitable openings through which the 65 tubes of the bank B² pass. Behind the bank of tubes B', and extending upwardly from the clamps H, and upper edge of the plate G, is a baffle wall E², which does not reach entirely to the drum A²; and behind the 70 rear bank of tubes B² a baffle-wall E³ extends from the drum A³ downwardly.

J indicates the smoke exit; K and L indicate doors through one of the side walls C² into the chambers K' and L' formed by 75 the dividing or barrier wall F between the fire wall D and rear wall C', so that ashes and dust can be removed therethrough from the chambers K' and L'.

In operation the fire-gas travels through 80 the furnace chamber as indicated by the arrows on the drawing, and is prevented from passing around the lower edge of the baffle wall E² by the baffle plate G and barrier wall F; the material in the pocket F' in 85 which the lower edge of the plate G is embedded forms a yielding seal around the edge of the plate G, and prevents the bypassing of fire-gas at that point, so that it must pass upwardly over the upper edge of 90 the baffle wall E²; and ashes and dust which may accumulate between the baffle walls E and E² can slide downwardly between the mud-drum A and baffle-plate G into the chamber L', thus rendering it unnecessary to 95 clean out the space between the baffles E and E² on the top of the drum A.

Having thus shown and described the construction and operation of my invention so as to enable others to utilize the same, what 100 I claim as new and desire to secure by Letters Patent is:

1. In a water tube steam generator, a boiler setting containing a fire chamber in the front portion thereof, a lower or mud drum, a fire wall under said drum, a rear upper drum, a rear bank of tubes connecting said mud-drum and said rear upper drum, another upper drum in front of said rear upper drum, a bank of tubes connecting the 110

same with said mud-drum, a baffle wall behind said last mentioned bank of tubes, the lower end of which is in spaced relation to said mud-drum, a baffle extending from the 5 lower end of said first mentioned baffle wall in spaced relation to said mud-drum transversely through said rear bank of tubes, and means to prevent the flow of fire-gas around the edge of said last mentioned baffle, 10 substantially as set forth.

2. In a water tube steam generator, a boiler setting containing a fire chamber in the front portion thereof, a lower or mud-drum, a fire-wall under said mud-drum, a 15 rear upper drum, a rear bank of tubes connecting said mud-drum and said rear upper drum, another upper drum in front of said rear upper drum, a bank of tubes connecting the same with said mud-drum, a baffle between said two banks of tubes the lower end of which is in spaced relation to 20 said mud-drum, a barrier wall behind said fire-wall, the upper edge of which is in spaced relation to the rear bank of tubes, a baffle extending from the lower end of said 25 first mentioned baffle wall in spaced relation

to said mud-drum transversely through said rear bank of tubes to the upper edge of said barrier wall, substantially as set forth.

3. In a water tube steam generator, boiler 30 setting walls containing a fire chamber in the front portion thereof, a lower or mud-drum, a fire-wall under said mud-drum, an upper rear drum, a bank of tubes connecting said mud-drum and said upper rear drum, 35 another upper drum in front of said upper rear drum, a bank of tubes connecting said last mentioned upper drum with said mud-drum, a baffle wall between said banks of tubes the lower edge of which is in spaced 40 relation to said mud-drum, a barrier wall between said fire-wall and the rear boiler setting wall, having a pocket in the upper edge thereof, a baffle extending from the lower edge of said first mentioned baffle transversely through said rear bank of tubes, and into the pocket in the upper edge of said barrier wall, and means to yieldingly seal the edge of said baffle in said pocket, substantially as set forth. 45

In testimony whereof I affix my signature.
LAWRENCE E. CONNELLY.
